UNITED STATES PATENT OFFICE.

FREDERICK B. LITTLE, OF INDIANAPOLIS, INDIANA.

ELECTRIC CONTROL APPARATUS FOR MUSICAL INSTRUMENTS.

1,239,609.

Specification of Letters Patent. Patented Sept. 11, 1917.

Application filed March 2, 1915. Serial No. 11,489.

To all whom it may concern:

Be it known that I, FREDERICK B. LITTLE, a citizen of the United States, and a resident of Indianapolis, in the county of 5 Marion and State of Indiana, have invented a certain new and useful Electric Control Apparatus for Musical Instruments; and I do hereby declare the following to be a full, clear, and exact description of the invention, such as will enable others skilled in the art to which it appertains to make and use the same, reference being had to the accompanying drawings, and to the characters of reference marked thereon, which 10 form a part of this specification.

My invention relates to musical instruments and has particular reference to musical instruments comprising a plurality of sets of electrically operated tone-producers, 20 a single key board and connections by means of which any one or more of the sets of tone producers can be operated from the key board.

My invention also covers a construction 25 particularly adapted for easy and rapid assembling and disassembling of the several parts to facilitate the convenient and rapid setting up and dismantling of the apparatus in various places for use, such as moving 30 picture theaters.

A further feature of my invention is the idea of providing electric lights related to the various tone-producers so connected that the lights will flash when respective tone 35 producers are sounded.

My invention resides in an electrical musical apparatus which includes a plurality of sets of electro-magnetically operated tone-producers, a single key board, a plurality of multiple switches, one for each set, 40 an electro-magnetic means for closing one or more of said multiple switches from the key board, whereby upon operation of the keys of the key board, corresponding tone producers of the connected sets shall sound.

My improved apparatus is particularly adapted for use in theatrical work when frequent changes of location necessitate the convenient and safe packing of and shipping 50 of the apparatus. I have arranged the several main sections of my apparatus, that is, the key board, the switch board and the musical instruments so that they can be quickly and easily detached from each other 55 for shipping and as readily connected for

operation. For this purpose the wires running from the switch board to each musical set are bound into a cable and the bar by which they are connected to the switch board is easily removable therefrom. In 60 like manner the key board is readily disconnected from and connected to the switch board. When disconnecting the apparatus for shipment the several connection bars are removed from the switch board and each 65 with its cable connected thereto is packed with the musical instrument or the key board with which the other end of the cable is permanently connected. Consequently, the spring tongue connectors which 70 might be damaged if they were to be removed from their positions are protected by the frame of the switch board.

In the drawings, Figure 1 illustrates a switch-board having thereon the circuit-controlling devices and the connectors for connecting the parts mounted on the switch board with the instruments. Fig. 2 is a sectional view of the connectors for the sets of circuits which are connected with the 75 sets of musical instruments taken on the line indicated in Fig. 1. Fig. 3 is an end view of the switch board shown in Fig. 1. Fig. 4 is an end view of a contact rod. Fig. 5 is a section of the master controlling magnet 80 which operates to disconnect the connectors connected in the circuits of the musical instruments. Fig. 6 illustrates the manner of mounting of one of the circuit changing keys. Fig. 7 illustrates the playing keys 85 which operate the sets of musical instruments and also one set of the circuit-changing keys which control the connections of the sets of instruments with the playing keys. Fig. 8 illustrates diagrammatically 90 the connections between the different instrumentalities used in connection with a system involving my invention.

1, Fig. 1, is the base of the switch board of any desired construction. 2 are supporting cross pieces mounted near the ends of the switch board 1. A plurality of bars numbered 5 to 14, inclusive, are supported on the cross pieces 2 and extend lengthwise of the board. They are disposed in parallel 105 arrangement and are secured to the cross pieces 2. The bars 6, 8, 10, 12 and 14 are so mounted that they may be easily removed from the cross pieces or re-attached when the switch board is to be reassembled by 110

the screws 19, while the bars 5, 7, 9, and 11 are pivotally supported on the cross-pieces 2.

The bars are provided with contacts numbered 20 to 29, inclusive. The contacts are secured by screws 19 to the bars or by any other suitable means. The contacts 20, 22, 24, and 26 are preferably elastic or yielding so as to allow a certain amount of rotation or movement of the bars 5, 7, 9 and 11. The bars 5, 7, 9 and 11, are hinged to the cross pieces by means of the hinges 30. The contacts or contact plates 21, 23, 25, 27 and 29 are fixed contacts and operate as the anvil contacts with reference to the movable spring contacts 20, 22, 24, and 26. The contacts 20, 22, 24, 26 and 28 are connected together by means of a conductor or bus bar 35 which runs transversely beneath the longitudinal bars 5 to 13, and the flexible wires 36 which extend up through holes 37 located in the strips 5, 7, 9, 11 and 13. The flexible wires 36 permit movements of the bars 5, 7, 9 and 11 when closing with the fixed contacts located on the bars 6, 8, 10 and 12. The contacts 21, 23, 25, 27 and 29 are connected to wires 40, 41, 42, 43, 44 which are bound together to form cables. The rods being connected to the cable may by reason of their removability be readily disconnected from the switch board together with the cables to which they are connected and the cable rolled up with the rods for purposes of transportation. To re-assemble, all that is necessary is to connect the rods to the cross pieces of the switch board by the screws 19.

The cable 45 contains wires which lead to the electric lighting circuit and to the circuit changing switches located on the switch board in the manner hereinafter described. It may be bound with the cable 44 to form the cable 49. The wires 45 terminate in the connectors 46 which may be clamped upon the posts 47 for making connection.

The contacts 20, 22, 24 and 26 are moved so as to close and make contact with the anvils or fixed contacts 21, 23, 25 and 27 by means of the magnets 50, 51, 52 and 53 which operate upon the armatures 54, 55, 56 and 57. The armatures are connected to the rods 5, 7, 9 and 11 and when they are drawn down by the magnets the contacts are closed. The magnets 50, 51, 52 and 53 are preferably iron-clad magnets.

The contacts 20, 22, 24 and 26 are normally held open by the operation of the springs 60 which are secured to the fingers 61 fastened to the bars 5, 7, 9 and 11 and to the cross piece 2.

The spring dogs or latches 65, 66, 67 and 68 are disposed in front of the magnets 50, 51, 52, and 53, respectively, and in such a position as to engage the armatures of the magnets when they are pulled down upon

the energization of the magnets. They operate to retain the contacts in closed position which are originally closed by the magnet. This avoids the necessity of keeping a constant supply of current to the magnets in order to keep the contacts closed. The spring latches 65, 66, 67 and 68 are connected to a master release magnet 70. The latches may be provided with hooks 71 while a rod 72 is connected to the armature 73 of the release magnet 70. The rod 72 is provided with pins 74 which are located so as to engage the hooks 71 and pull the spring latches away from the armatures of the magnets when the release magnet is energized, thereby causing the release of any and all of the armatures that may be engaged by the latches. Immediately upon release of the armatures the springs 60 operate to lift the movable contacts away from the fixed contacts and thus disconnect the circuits that have been closed by the operation of the magnets and which have been retained in a closed condition by the latches which hold the armatures in their closed or contact making position.

The magnet 70 is preferably provided with a movable core 80 as well as an armature 73. The core 80 extends inwardly into the coil of the magnet 70 which is wound upon a brass spool 82. The rod 72 is preferably made of a non-magnetic material and is threaded into the armature 73. The magnet 70 is supported on a bracket 83 which is attached to the base 1. The core 80, armature 73 and the rod 72 are guided by the core fitting into the brass spool 82 and by means of the bracket 84 in which the outer end of the rod 72 is located and through which it extends. The rod 72 is yieldingly held in its outermost position by a spring 85 which presses against one of the pins 74. When the rod 72 is pulled inward by the operation of the release magnet 70 it not only pulls against the hooks 71 attached to the spring latches but also pulls against the spring 85 which operates to pull the rod and the armature 73 away from the magnet. The rod 72 is provided with an adjustable stop 86 which abuts against the bracket 84 which operates to limit outward movement of the rod 72 by the operation of the spring 85.

A block 90 is supported on the base 1. A plurality of circuit-changing keys 101 are supported on the top of the block 90, which are connected to the source of current through the connectors 94, see Fig. 6. Contacts 95 of this series operate upon contacts 92, see Figs. 6 and 7, which are connected with the release magnet 70, see Fig. 8. Further, the contacts 96, 97, 98 and 99 of this series operate to close with contacts 92 that are connected with the magnets 50, 51, 52 and 53, respectively. The contacts 95, 96, 97, 98 and 99 are supported on the rod 93. 180

The contacts 92 are connected through suitable connectors 100, see Fig. 6, with the magnets 50, 51, 52 and 53 and with the release magnet 70, as hereinafter described.

5 The contacts or keys 95, 96, 97, 98 and 99 control connections between keys 110 and sets of electric musical instruments. The keys 110 may be located in any position such as, in front of the stage of a theater, while 10 the part having the circuit-changing keys may be located in any part of the theater convenient where the times to make the desired changes may be noted. While the operator is operating on the keys 110 the circuit 15 changing keys may be manipulated so as to change the connection between the keys 110 and the sets of instruments, as may be desired. By this means any number of sets of instruments or any combination of 20 sets of instruments may be switched into connection with the keys 110, thereby producing such musical or spectacular effects as may be desired by one who is located on the stage or platform and where such a one 25 will have full knowledge of the effects to be produced.

The playing keys may be located in any convenient position, but I have found it preferable to mount the keys 110 in the 30 vicinity of the piano, which is commonly found in a theater in front of the stage. The keys are so constructed and mounted that they may be attached to one end of the key board of the piano in the manner shown in 35 Fig. 7. The keys 110 are mounted in the case 111 and are substantially of the same form as the keys of a piano. The case 111 is attached to a bracket 112 having a clamping screw 113, whereby the case 111 containing 40 the keys 110 may be clamped to the casting 114 of the piano. The case 111 having the keys 110 is attached so that the keys 110 are substantially in the plane of the keys 115 of the piano, preferably parallel therewith. The electrical key-board is located 45 at one side of the center of the piano and in such position as to expose all of the piano keys for use, so that the operator can play upon the piano and upon the electric key-board simultaneously or alternately, and with either or both hands as may be desired, 50 without altering or changing the position of the electric key-board.

The keys 110 are mechanically connected 55 with suitable contacts which are closed by the operation of the keys in the manner hereinafter described.

Also in the vicinity of the keys 110 and the piano keys are located circuit changing 60 keys 120 which are in construction a duplicate of the circuit changing keys 95, 96, 97, 98 and 99 shown in Figs. 3 and 6. The circuit changing keys 101 and the circuit changing keys 120 are connected in parallel 65 relation in the circuits as hereinafter de-

scribed, so that the sets of instruments may be controlled by either set of circuit changing keys.

The circuit changing keys 120 are located intermediate the key board of the piano and 70 the key board containing the keys 110. They are located in such a position that the circuit changing keys are in proximity to the keys of either key board whereby the operator may finger the keys of the key board 75 120 with the same hand that the other key boards are fingered. He may operate the keys of the key board 120 while holding any one of the keys 110 down. Also the keys of the key board 120, which correspond to the 80 keys 95, as indicated in Fig. 3, are located beside each of the controlling keys 96, 97, 98 and 99, which control sets of instruments so that the release magnet 70 may be caused to disconnect any set of instruments from the 85 control of the keys 110 and the adjoining key which controls the set that is desired to be played may be operated, without changing the position of the hand; that is, the release magnet keys are located beside each 90 one of the controlling keys whereby the operator may change the set of instruments which are being played while holding one of the keys 110 down in its operative position.

Also by my invention is provided a switch 95 126 for cutting off the connection to the playing keys and thereby preventing operation of any instruments by the operation of the key board.

Also by my invention is provided a light 100 controlling switch 127 whereby lights associated with the musical instruments may be controlled by the operator.

The system involving the several instrumentalities which have heretofore been described is illustrated in Fig. 8.

In Fig. 8 is illustrated the system showing the electric connections between the several instrumentalities involving or containing my invention. 130 is the source of current supply for operating the electromagnetically controlled switches and the musical instruments. It may be any suitable source of current supply. It is preferably a source of direct current and I have found 110 that a storage battery is probably preferable to any other form of current supply. The storage battery 130 is connected to a plug 131 which may be inserted between contacts 132 located in a suitable socket. 120 133 and 143 are bus bars which are connected to the contacts 132. From the bus bars 133, 143 the circuits branch into two parts 150 and 140, 150 connecting with the controlling magnets 50, 51, 52, 53, and 70 and 125 120 through the magnet coils with the switches 101 and 120 and the branch 140 supplying current to the musical instruments 135, 136, 137 and 138 and the controlling switches 110, and 20-27, inclusive, which cause the 130

operation of the musical instruments. In the branch 140 leading from the bus bar 133 are located the contacts 28 and 29 which are carried by the rods 14 and 13 on the 5 switch board. The current then passes through the switch 126 which controls the playing keys thence it divides to the playing keys 110 and passes through the pair of contacts which are closed by the operator's finger and thence it goes through contacts 29 and 28 to the contacts which are controlled by the magnets 50, 51, 52 and 53. The current will pass through the contacts which are connected to the rod which is held 10 down by the latch of a magnet that has been energized. In the drawing the magnet 53 has been energized so that the current will then flow through the contacts 26 and 27 to one of the bells of the set 138. It will 15 go to that bell that corresponds to the key 110 that is closed by the operator. Thence the current flows from the set 138 to the contact 26 and 27 of the return line to the bus bar 143 and thence it returns to the 20 battery 130. When the magnet 52 has been energized and its armature and the bar 9 attached thereto have been turned so as to close the contacts 24 and 25 and the armature and bar held in contact closing position 25 a similar circuit will be established through one of the instruments of the set 137 instead of through one of the instruments of the set 138. The same is true with reference to the magnet 51 and the set 136 and 30 the magnet 50 and the set 135. Any combination of sets may however be obtained in the operation of the system.

The other branch 150 of the circuit from bus bar 133 contains the controlling magnets 40 50, 51, 52, 53 and 70 and the circuit-changing keys 101 and 120. The current passes from the bus bar 133 to the magnets 50, 51, 52, 53 and 70 and thence it passes to the circuit-changing keys 101 and to the 45 circuit changing keys 120 which are connected in parallel. They are connected to the bus bar 143 thence the circuit is completed to the storage battery 130. Upon the operation of the keys 96, 97, 98 or 99, or 50 the circuit changing keys 120 on the keyboard, the magnets 50, 51, 52, or 53, respectively, will be energized. The magnets will pull their associated armatures down so as to be engaged by one of the hooks 65, 66, 55 67, 68 according to which of the magnets is energized, closing thereby the contacts 20, 22, 24 or 26, which are connected to the armature of the magnet energized. In order to release the armatures and consequently 60 open the circuits of the contacts 20, 22, 24 or 26 as the case may be, any one of the keys 95 of the set 101 or the corresponding keys of the set 120 may be operated whereupon the releasing magnet 70 will be energized, the circuit being completed through

the keys 95 to the bus bar 143 and thence back to the storage battery 130. When the release magnet 70 is energized it will pull the rod 72 which will engage with the hooks 71 and pull out the latches and permit the contacts which have been closed by one of the magnets to be opened. Whereupon, another of the magnets or any number or combination of the magnets 50, 51, 52, or 53, may be energized which will cause the 75 latches to engage with their respective armatures and hold the contacts closed which will cause any one or any number or any combination of the sets of instruments to be operated by the playing keys 110. 80

A means is also provided for connecting a lighting system with the instrument-playing system whereby the set of instruments which are being operated will be illuminated. 160 is the source of electric light supply and is connected by means of a suitable socket 161 to the switch board 1 through which it is connected to the controlling switches and the electric lamps, the electric lamps being located in the vicinity of the different sets 85 of instruments which are being operated upon by the operator. The source of current supply 160 is connected to the bus bars 162 and 159. 90

The sets of instruments are preferably located on racks and electric lamps are preferably mounted above the instruments and in front of reflectors. The connections and controlling switches are such that when any particular set of instruments is played or 95 any number of sets of instruments are being played a flood of light will be produced by the electric lamps associated with the set or sets of instruments that are being played, which gives a distinction over and above the 100 other sets of instruments that are out of circuit and not being operated upon. 105

The circuit thence passes from the bus bar 162 to the clip 46 and the switch 127, 110 thence it returns to another of the clips 46 and to the switches 163 and thence it passes to the contacts 20, 22, 24 and 26 which are controlled by the control magnets 50, 51, 52, and 53; thence it passes to the electric lamps 165, 166, 167, 168 according as the contacts 115 20, 22, 24 or 26 are closed by the magnets 50, 51, 52 or 53 and held closed by the latches. So that the instruments 135, 136, 137 or 138 which receive their current through the set of contacts 20, 22, 24, or 26 as it is being played by the operator by closing the playing keys 110 will be illuminated with the lamp associated with such instruments as are thus being played. The 120 circuit returns from the contacts 20, 22, 24 or 26 as the case may be, to the bus bar 159, thence it returns to the source of supply 160. The switch 170 has two switch bars connected together to be operated simultaneously; one bar is in the circuit connecting 125 130

the source of supply 130 with the playing circuits, and the other is in the circuit connecting the source of supply 160 with the lighting circuit. Consequently when the 5 switch 170 is closed, current is supplied to both the playing and lighting circuits, and when it is opened the current is cut off from both these circuits. In Fig. 1, I have shown the switch 170 as a lock switch. It may be 10 locked open or locked closed, which prevents any tampering with the system.

The switch 126 is located in the circuit of the playing keys 110 and when opened will prevent any of the instruments being played 15 by the keys 110. The switch 127 will also prevent the lamps from being lighted during the operation of the instruments. The switch 125 is located in the common connection of the circuit changing keys 120 which 20 when opened will prevent the operation of any of the controlling magnets 50, 51, 52, 53 and 70. The switches 163 will, when opened, cut out or prevent the lighting of any of the lamps of any particular set of 25 instruments.

Also, suitable fuse 175 may be connected in the system for protection of the electric lamps. Other suitable safety devices may be connected in the circuits of the system as 30 may be desired.

The system may be used for operating any form of electric musical instruments or any number of forms of musical instruments. I have shown the system as operating various 35 sets of instruments which produce their tones by vibrating magnets and single stroke magnets. I have shown a set 138 of electric musical bells, a set 137 of single tone steel bars; a set 136, of double tone steel bars, and a set 40 135, of cathedral chime tubes. The chime tubes are operated by magnets, each of which makes a single stroke when producing the tone, while the other instruments are operated by vibrating magnets to produce the 45 desired tones. The system however, may operate instruments of any design.

The arrangement and connection of the instruments and their construction may be greatly varied. Elements having equivalent 50 functions may be substituted and such modifications may be used for many varied purposes and still contain the invention.

Having thus described my invention, what I claim as new, and desire to secure by Letters Patent, is,—

1. A key board, a plurality of keys carried by the keyboard, a plurality of musical instruments, each instrument comprising a plurality of electro-magnetically-operated 55 tone producers, a switch board, a plurality of multiple circuit closers on the switch-board, one for each musical instrument, each multiple circuit closer comprising a set of stationary individual contacts connected with the tone producers of its respective in-

strument and a movable switch bar carrying coöperating contacts, bus bars connecting corresponding coöperating contacts of the several movable switch bars, switches on the key board one for each circuit closer and 70 connected therewith for operating the same, a single pair of contacts operable by each key, and connections between said key contacts and said bus bars on the switch board whereby when any key is operated current 75 will pass to its connected bus bar and the tone producers of the musical instruments will be sounded which are connected with the multiple circuit closers which are in closed position.

2. In a semi-portable electro-magnetically operated musical apparatus a plurality of sets of electro-magnetic musical tone producers, a key-board, a single circuit closer for each key, a switch-board, a plurality of 80 multiple contact bars removably mounted on the switch-board one for each set of musical tone producers, a series of contact plates on each bar, one plate for each tone producer of its set, a flexible cable connecting the 85 tone producers of each set with its associated multiple contact bar, a removable key-board contact bar on the switch-board having a contact plate for each key, a flexible cable connecting said removable key-board contact bar with the contacts of the keys whereby the musical sets, the switch-board and the key-board are readily disconnected for shipment and are readily connected for operation.

3. In a knock-down electric musical instrument a key-board, a switch-board, a removable multiple contact bar on the switch-board, a contact thereon for each key, an electrical cable connecting the contacts with 105 respective keys, a plurality of sets of electro-magnetically operated musical tone producers, a plurality of removable contact bars on the switch-board one for each musical set and having a contact for each tone producer 110 in the set, a cable connecting the tone-producers of each set with the contacts of the respective bar on the switch-board, a multiple point switch bar for each contact bar and connections between the points thereof 115 and respective contacts of the removable contact bar connected to the keys, whereby the switch-board can be disconnected from the key-board and from the musical sets for shipment.

4. In a semi-portable electro-magnetically operated musical apparatus a plurality of sets of electro-magnetically operated musical tone producers, a key-board, a circuit closer for each key, a switch-board, a plurality of 120 multiple contact bars removably mounted on the switch-board one for each musical set, a series of contact plates on each bar, one plate for each tone producer of its set, a flexible cable connecting the plates of each 125

removable bar with the tone producers of its set, a removable key-board contact bar on the switch-board having a contact for each key, a flexible cable connecting said removable key-board contact bar with the circuit closers of the keys, a plurality of bus bars on the switch-board, one bar for each key and a multiple switch bar on the switch board for each removable bar having a 5 spring plate for contact with the respective contact of the opposed removable bars, those for musical sets being mounted on rocking bars for simultaneously closing and opening all of the playing circuits of each set and 10 connection between the said spring contacts and respective contacts of the removable key board contact bar, a source of electricity one pole connected with the key circuit closers and the other connected with the electro- 15 magnetic tone producers.

5 The improvements herein described comprising a set of musical electro-magnetically operated tone producers, a playing key-board, one key for each tone and each 20 having a circuit closer; a switch-board intermediate the key-board and the sets of tone producers, a plurality of bus bars on the switch-board one for each key and electrically connected therewith; a plurality of 25 series of contact plates on the switch-board one series for each set of tone producers and electrically connected with the respective tone producers, a plurality of series of 30 spring contacts corresponding with and adapted to contact with the respective contact plates and electrically connected with the respective key bus bars; means normally holding said spring contacts out of circuit 35 closing position, a plurality of electro-magnetic devices on the switch-board, one for 40 each said series of spring contacts, a plurality of electric switches on the key-board, one for each set of electro-magnetic devices and electrically connected therewith for controlling the same, means for retaining the 45 spring contacts in circuit closing position and means operable from the key-board for

releasing the latter; a source of electric current one pole thereof connected with the key-board, the other pole thereof connected with 50 the electro-magnetic tone producers whereby when a key is depressed the corresponding tone will be sounded in each musical set, the corresponding spring contacts of which are 55 in closed position.

6. In a musical instrument a plurality of sets of electro-magnetically controlled tone producers, a key-board, electrically controlled means whereby any desired instrument can be played from the key-board, 60 electric lamps associated with each set of tone producers, and means whereby the lamps associated with respective instruments will be automatically switched on when the particular instrument is being 65 played.

7. In a musical instrument a plurality of electro-magnetically controlled tone producers, a key-board for operating said tone producers, electric lamps associated with 70 said tone producers for illuminating them, and means whereby the particular tone producers being operated will be automatically illuminated.

8. In a musical instrument, a key-board, 75 a plurality of sets of musical instruments having electro-magnetically controlled tone producers, each key having a single circuit closer adapted to be electrically connected to 80 respective tone producers in said instruments, a normally open multiple electro-magnetic circuit-closer for each set, a switch on the key-board for each said multiple circuit-closer connected therewith for closing the same, and means controlled from the 85 key-board for releasing said multiple circuit closers.

In testimony whereof, I have hereunto signed my name to this specification in the presence of two subscribing witnesses.

FREDERICK B. LITTLE.
